UNITED STATES PATENT OFFICE

170,297

TRAILER

William Aschenbrenner, Denver, Colo.

Application October 30, 1952, Serial No. 22,059

Term of patent 7 years

(Cl. D14—3)

To all whom it may concern:

Be it known that I, William Aschenbrenner, a citizen of the United States, residing at Denver, State of Colorado, have invented a new, original, and ornamental Design for a Trailer, of which the following is a specification, reference being had to the accompanying drawing, forming a part thereof.

Fig. 1 is a side elevation of a trailer embodying my new design;

Fig. 2 is a rear view of the trailer of Fig. 1;

Fig. 3 is a perspective view of the trailer, taken from a point at the front, and to one side; and

Fig. 4 is a perspective view of the trailer, taken from a point at the rear, and to one side.

I claim:

The ornamental design for a trailer, as shown.

WILLIAM ASCHENBRENNER.
